UNITED STATES PATENT OFFICE

WILLIAM L. HANCOCK AND BRONSON C. WOODFORD, OF DALLAS, TEXAS, ASSIGNORS TO
THE MURRAY COMPANY, OF DALLAS, TEXAS, A CORPORATION OF TEXAS

COTTON BALING PRESS

Application filed June 4, 1928. Serial No. 282,753.

This invention relates to new and useful improvements in cotton baling presses.

One object of the invention is to provide an improved press frame possessing greater stability and making for simplicity, efficiency and compactness in mounting the ram head, boxes, trumper and other parts.

Another object of the invention is to provide in the lower boxes inside corner guide 10 angles arranged vertically for securing the box together in a substantial manner, for guiding the bale and also for providing stops for the lower ends of the end doors.

A further object of the invention is to construct the upper and lower boxes with a continuous upward flare for the purpose of relieving the frictional resistance offered to the upward movement of the bale, as it is compressed; also whereby condensation of the 20 cotton under the trumper is assisted.

A still further object of the invention is to provide the upper edges of the end and side doors with inward bevels to prevent the lint cotton from wedging between the said doors 25 and the top platen.

Another object of the invention is to provide sheet metal protectors for the battens of the top platen and the follow block, to facilitate threading the bale tie bands between the battens.

A particular object of the invention is to provide an upper box wherein the side doors are provided with angle braces for the end doors, extending the full height of the box, 35 and preventing bulging or warping of the doors and making for greater safety while the bale is being compressed.

An important object of the invention is to provide the follow block with depending legs 40 at each corner operating contiguously to the corner angle guides of the lower box, and hanging below the sill of the upper box, when the side doors are open, to prevent the cotton bale jumping from the box when one of said side doors is first opened.

A construction designed to carry out the invention will be hereinafter described, together with other features of the invention.

The invention will be more readily understood from a reading of the following specifici-

cation and by reference to the accompanying drawings, in which an example of the invention is shown and wherein:

Fig. 1 is an elevation of a baling press constructed in accordance with the invention, 55

Fig. 2 is an end view of the same, partially in section and partially in elevation,

Fig. 3 is a horizontal cross-sectional view taken on the line 3—3 of Fig. 1,

Fig. 4 is an enlarged transverse vertical sectional view taken on the line 4—4 of Fig. 1, 60

Fig. 5 is a sectional view of the upper center bearing,

Fig. 6 is a detail of the box support,

Fig. 7 is a detail of the lower center bearing, 65

Fig. 8 is an enlarged partial end elevation of one of the boxes,

Fig. 9 is a horizontal cross-sectional view of one corner of one of the boxes, 70

Fig. 10 is a horizontal cross-sectional view taken on the line 10—10 of Fig. 1.

In the drawings the numeral 10 designates the upright end channel member of a press frame. This channel is secured at its bottom between channel sills 11. At the opposite ends of the sills twin braces 12 are fastened between said sills (Fig. 3) and the lower end of a center post 13 is fastened between said braces. The sills constitute the 80 base of the frame and provide a substantial support.

The center post is preferably in the form of an H-channel, but this is subject to variation. Top platens 14 are secured on each side 85 of the upper end of the end member 10 and have their inner ends connected by a brace 15 (Fig. 10), which is supported on the upper end of the post 13. The platens also support a mast head 16 contiguous to the brace 90 and this head supports one end of a pair of girders 17 on which the trumper (not shown) is supported. The outer ends of the girders are carried by a standard 18 mounted on the floor 19'. 95

The parts which have been described form the press frame which, aside from its sturdy and rigid construction, has many advantages, some of which will be hereinafter pointed out. While channel members have been 100

shown and described and possess considerable value, the invention is not to be limited to the same. The parts may be bolted, riveted or otherwise secured, but bolting is preferable as it permits dismantling and assembling, thereby facilitating transportation and shipping.

In cotton presses of the double box type it is advantageous to have the boxes mounted 10 for ready turning and easy handling. In providing this feature an elongated box frame 19 is centrally mounted on a turntable 20 (Fig. 7). The turntable is carried on ball bearings 21 mounted in the race of a bearing 15 sleeve 22.

As is shown in Fig. 1, the sleeve rests upon a stool 23 supported on set screws 23' resting on the base sills. The parts are substantially supported, capable of sustaining heavy 20 loads and readily manipulated. By adjusting the screws 23' the sleeve is moved vertically and the lower bearing and boxes are brought to the proper elevation.

Lower boxes 24 have their lower ends secured 25 within the box frame 19 on each side of the turntable, the inner end panels of said boxes resting in seats 25 on opposite sides of the turntable. The boxes are formed of upright boards and also supported in an upper 30 frame 26, similar to the frame 19. Diagonal angle braces 27 are fastened to the sides of the boxes, diverging from the center of the lower frame. The usual circular platform 28 surrounds the boxes and is carried on the upper frame 26 (Figs. 1, 2 and 4). Struts 29 inclined from the frame 19 support the outlying portions of the platform and provide a rigid structure.

In order to prevent tilting of the boxes and 40 platform due to the action of the tamper and the ram and also to support the boxes, shoes 30 are fastened on the ends of the lower frame 19 (Figs. 1 and 6). On the side opposite the sills 11 a pillow block 31 is mounted 45 on a base 32. A thrust roller 33 mounted in a bearing pedestal 34 receives and supports one of the shoes.

An important feature resides in angular 50 vertical corner guides 35 (Fig. 4). These metal guides being secured in the corners of the boxes not only form guide-ways for the follow block, but securely tie the ends and sides of the boxes together. The guides extend beyond the upper edges of the boxes. 55 The boxes also extend above the platform.

Upper boxes comprising end doors 36 and side doors 37 are mounted on the lower boxes. End bars 38 (Figs. 2 and 8) are arranged 60 transversely across the upper ends of the lower boxes and have hinge brackets 39 secured to their ends. Hinge shafts 40 are journaled in said brackets and the lower portions of the side doors are fastened on said shafts by angle bars 41; each shaft being 65 square, in cross-section, between said bars

and round where it passes through the brackets.

The upper ends of the guides 35 are cut off at the level of the shafts, so as to leave end lugs 42 extending above the upper edges 75 of the ends of the lower boxes. These lugs form inner stops for the lower ends of the end doors 36. The meeting edges of the doors 36 and the end panels of the lower boxes are beveled outwardly and downwardly (Fig 5), whereby said doors are retained behind the bars 38.

The end doors have vertical angular stays 43 resting on end bars 38. Stops 44 carried 80 on the outer faces of end doors rest upon the end bars. The side doors 37 have vertical angle cleats 45 overlapping the vertical edges 85 of the end doors 36, thus bracing said end doors against outward displacement.

Suitable retaining dogs 46 project through 85 slots 47 in the side doors and may be of any suitable construction, such as is shown in co-pending application filed April 30th, 1928, Serial No. 274,030. The side door may be fastened in any suitable manner, as by the 90 means also shown in said co-pending application. The fastening means and the dogs form no part of this invention. In general the door fastening means comprises keeper hooks 48 carried by the end doors and latch 95 bars 49 mounted on the side doors and engaging said hooks.

An upper centering bearing includes a spreader 50 (Fig. 5) having beveled ends 51 engaging in the channel bars 38 at the center 100 thereof. A sleeve 52 has its lower end resting in an annular seat 53 in the spreader and surrounding the post 13. The turntable 20 rotatably supports the boxes, while the spreader 50 and sleeve 52 center said boxes, 105 thus assuring easy rotating and maintaining vertical alinement. One of the features is that the turntable 20, sleeve 22, stool 23, spreader 50 and sleeve 52 are all split vertically, thus permitting said parts to be assembled on the post and suitably bolted in 110 place after the frame is erected.

The side doors may be counterbalanced in any suitable manner and we have shown (Fig. 8) arms 54 fastened on the inner adjacent ends of the shafts 40. These arms each have a grooved rocker 55 to one end of which a chain 56 is connected; said chain supporting a coiled spring 57 attached to the lower box frame 19. This construction is 115 not a part of this invention.

When one of the side doors 37 is swung outward, its hinge shaft 40 will swing the arm 54 attached thereto, thus picking up the chain 56 and tensioning the spring 57 and thereby counterbalancing said door. Any suitable device may be used for this purpose.

A top platen 58 composed of spaced bats is secured to the bottoms of the beams 14 and a metal guard sheet 59 is secured on top 130

of the platen. The bottom of each lower box is open and a follow block 60 is supported therein. Each block includes spaced bats 61 secured transversely of channel bars 62, between which are mounted I-beams 63 (Figs. 1, 2 and 4). A metal protector sheet 64 is fastened under the bats. The sheets 59 and 64 prevent the bale tie bands projecting beyond the bats and confine said bands to the spaces between said bats.

The block includes a cap plate 65 secured to the under side of the bars 62 and beams 63 for receiving the cap 66 of the ram plunger 67. The sills 11 permit the use of an inverted ram head 68 fastened on said sills and depending therebetween. The ram cylinder 69 is secured to the head. This structure affords a saving of several inches in height between the sills and the bottom of the lower box.

Each follow block 60 is of such area as to slide freely in the guides 35 and is carried upward in the boxes by the ram plunger 67. Each lower box 24 and the adjacent upper box formed by the doors 36 and 37 is flared upwardly. As this flare is only about one inch in several feet, it is not shown in the drawings. The advantage of this flare is that the skin resistance offered by the side walls of the boxes to the upward compression of the cotton, is reduced. When the box is under the tamper the upward flare will have a condensing effect because the cotton is forced from the wider upper end to the narrower lower end, thus producing more efficient tramping.

Each follow block has depending legs 70 which hang in the upper ends of the guides 35 when the side doors are open, thus preventing the block from jumping out of the box.

It will be noticed (Fig. 4) that the upper edges of the doors 36 and 37 are bevelled inwardly. This prevents the cotton from wedging between said doors and the bats of the top platen 58.

The doors of the upper boxes are conveniently and efficiently arranged. When the upper box is assembled the end doors 36 are merely set into the seats formed by the end bars 38 and the bevel edges of the end panels of the lower boxes (Fig. 5). Upon opening the side doors 37 the cleats 45 are withdrawn and the end doors 36 swing outward 55 against the post 13 and the channel 10, their lower ends being retained by the lugs 42.

In setting the press frame it is necessary to have the sills 11 substantially level and as these sills are usually placed on a concrete slab or other rigid flat support, set screws 11' are provided in the lower flanges of the sills 11 so as to bear on the surface of the concrete slab. By adjusting these screws, the sills, and consequently the press frame, 65 may be levelled. This is particularly ad-

vantageous over the wedges and blocks usually employed.

When the tamper (not shown), which is mounted on the girders 17, is operating to press cotton in the box, there will be an upward strain upon the said girders. To counteract this upward strain, a tie rod 71 has its lower end secured in the base 32, while its upper end is connected to an eye bolt 72 extending through the floor 19' and bracketed to the standard 18. This is another important feature and lends stability to the press.

Various changes in the size and shape of the different parts, as well as modifications and alterations, may be made within the scope of the appended claims.

What we claim, is:

1. In a cotton press, a center post, transverse channel bars on each side of the post, press boxes having their ends secured to said bars, a spreader having opposite extensions engaging in said channel bars and surrounding said post, and a bearing member fastened on said post and engaging in said spreader for centering the press boxes.

2. In a cotton press, a press box having its upper portion composed of end and side doors, the side doors being hinged to the sides of the box, angle members secured vertically in the corners of the box and extending above the ends of the box, cross bars on the upper end of the box, the end doors being held between the cross bars and the upper ends of the angle members embracing members carried by the side doors and over-lapping the vertical edges of the end doors, and a follow block slidable vertically in the box, the angle members forming guides for the follow block.

3. In a cotton press, a pair of horizontal metal base sills, an upright metal end member, a central metal post angular in cross section, horizontal platen beams secured to each side of the upper end of the end member and also fastened to each side of the upper end of the post, a spreader rotatable around the post, a bearing member fastened on the post and engaging the spreader, press boxes engaged and spaced by the spreader, a turn table rotatable around the post and secured to the ends of the boxes, and a stool mounted on the base beams and rotatably supporting the turn table.

4. In a cotton press, a metal frame, a center metal post angular in cross section and secured in the frame, a spreader rotatable around the post and free from contact therewith, an upper bearing member fastened on the post and engaging the spreader, press boxes engaged and spaced by the spreader, a turn table rotatable around the post and free from contact therewith and secured to the ends of the boxes, a stool mounted on the

base of the frame, and a bearing member carried by the stool and secured about the post for supporting the turn table.

In testimony whereof we affix our signatures.

WILLIAM L. HANCOCK.
BRONSON C. WOODFORD.
